(57) **CLAIM**

The ornamental design for a coffee capsule, as shown and described.

DESCRIPTION

FIG. 1 is a top isometric view of a coffee capsule showing the new design.

FIG. 2 is a bottom isometric view thereof.

FIG. 3 is a side view thereof.

FIG. 4 is a bottom view thereof.

FIG. 5 is a top view thereof; and,

FIG. 6 is a cross-sectional view thereof taken at line **6-6** of FIG. 3.

The broken lines shown in the drawings illustrate portions of the coffee capsule that form no part of the claimed design.
